UNITED STATES PATENT OFFICE.

DANIEL WEBER, OF READING, PENNSYLVANIA.

HAT-BOX.

No. 895,521.

Specification of Letters Patent.

Patented Aug. 11, 1908.

Application filed April 17, 1908. Serial No. 427,631.

To all whom it may concern:

Be it known that I, DANIEL WEBER, citizen of the United States, residing at Reading, in the county of Berks and State of Pennsylvania, have invented certain new and useful Improvements in Hat-Boxes, of which the following is a specification.

This invention relates to improvements in hat boxes, and my object is to provide a box in which a number of hats may be packed for shipment, each hat being properly spaced and protected from contact with its neighbor or with the inner wall of the box.

My object has been to construct a spacing device that will be simple in construction, one that is easy to assemble and place in position and one that will require no pasting or other fastening means. To this end I provide a panel, preferably of card board having slits therein, whereby four like panels may be joined to form a nest or support of substantially rectangular outline.

The support when assembled may be folded, or the panels may if preferred, be left separate, when being prepared for shipment, in either case the minimum space is required.

Having thus fully described the object of my invention, the device is more fully described in the following specification and clearly illustrated in the accompanying drawing, in which:—

Figure 1 is a plan view of a box with my support therein. Fig. 2 is a vertical central sectional view thereof. Fig. 3 shows the hat support folded. Fig. 4 is a detail of one of the panels from which the support is made up.

The numeral 1 designates an ordinary hat box of substantially circular outline.

2 designates the hat support. This support is made up of four panels, each of which is formed with two slits 3 extending approximately one-half its width, while the longitudinal edges thereof are set at right angles thereto, as shown at 4, although these edges are shown flat, they may, if desired, be curved so as to present a smaller contact surface for the hat brim, but still not sufficiently sharp to mark said brim, as would be the case with the edge of the board. When four of these panels are joined together as shown, by slipping them over each other at their slits, and forming a substantially rectangular

body, it is placed in the box and the ends of the panels will contact with the inner wall of the box, thus preventing any movement of the support therein. The hat is placed, upside down, with the crown in the center space 5 formed by the panels, and the brim will rest on the overturned edges 4. This operation is repeated until the box has received its full capacity, and it will be seen that each hat will not only be properly spaced and supported but will be held positively central in the box and proof against contact with each other or with the wall of said box. It is probable that a support may be made up of three of these panels for use in certain cases, forming a triangular body, or that other slight modifications may be made without departing from the spirit of my invention, and I do not therefore wish to limit myself to the exact form of device shown and described, but:—

What I claim and desire to secure by Letters Patent is:—

1. The combination of a circular hat box, with a hat support comprising four panels, each of which is formed with slits extending approximately one-half its width and having its longitudinal edges set at right angles to the body, said panels being adapted to be removably secured together at said slits to form a substantially rectangular support.

2. The combination with a hat box, of a support comprising a plurality of slitted panels removably joined together at said slits and having their longitudinal edges set at right angles to the body.

3. A hat support made up of four slitted panels joined together at said slits, each of which has its longitudinal edges set at right angles to the body thereof and adapted to receive the crown of a hat in the center space formed by said panels.

4. A hat support comprising a plurality of slitted panels joined together at said slits and having their longitudinal edges bent out of line with the body thereof.

In testimony whereof I affix my signature, in presence of two witnesses.

DANIEL WEBER.
